UNITED STATES PATENT OFFICE.

JOHN C. VIRDEN, OF CLEVELAND, OHIO.

DESIGN FOR A CHAIN-LOOP.

58,002.

Specification for Design.

Patented May 24, 1921.

Application filed August 17, 1920. Serial No. 404,284. Term of patent 7 years.

To all whom it may concern:

Be it known that I, JOHN C. VIRDEN, a citizen of the United States, residing at Cleveland, Ohio, have invented a new, original, and ornamental Design for Chain-Loops, of which the following is a specification.

The design is shown in the accompanying drawings in which Figure 1 is a front elevation of my chain loop; Fig. 2 is a side elevation thereof and Fig. 3 is a plan view of said loop.

The design has nothing to do with the mode of attachment but has sole reference to the structural part which shows when in use and is male threaded or female threaded to correspond with the threading of the member to which it is to be attached.

In the drawings the dotted lines indicate one form the thread may take.

I claim as my invention:

The ornamental design for a chain loop substantially as shown.

J. C. VIRDEN.
